UNITED STATES PATENT OFFICE.

JULIUS L. MICHALSKI, OF MILWAUKEE, WISCONSIN.

DISPLAY DEVICE.

1,407,874.

Specification of Letters Patent. Patented Feb. 28, 1922.

Application filed August 23, 1920. Serial No. 405,237.

To all whom it may concern:

Be it known that I, JULIUS L. MICHALSKI, a citizen of the United States, and resident of Milwaukee, in the county of Milwaukee and State of Wisconsin, have invented certain new and useful Improvements in Display Devices; and I do hereby declare that the following is a full, clear, and exact description thereof.

10 My invention relates to new and useful improvements in display devices, which are particularly adapted to be used in connection with barbers' poles and the like.

The primary purpose of the invention is 15 to provide a display device which, in addition to having the usual distinguishing characteristics, includes means for displaying various kinds of advertising matter.

It is also an object of the invention to 20 provide a display device of this character having means whereby advertising display signs of an interchangeable nature may be used.

With these general objects in view the 25 invention resides in the novel features of construction, combination and arrangement of parts which will be hereinafter more particularly described and claimed, and shown in the accompanying drawing, wherein—

30 Figure 1 represents a side elevational view, with parts broken away of a barber's display device constructed in accordance with the invention, and

Figure 2 is a detail transverse section on 35 the plane of the line 2—2 of Figure 1.

Referring more particularly to this drawing, it will be seen that the reference character 1 denotes a vertically positioned hollow casing of a suitable size and length 40 which has a globe 2 mounted on its upper end. Insofar as the present invention is concerned, the cross sectional shape of the casing 1 and the length and location thereof is immaterial. That is to say, the casing 45 may be square in cross section as shown in Figure 2, rectangular, circular or any other shape and its height is largely dependent upon its location, either on the ground or spaced thereabove.

50 In any case a vertically positioned opening is formed in the casing and is normally closed by a door 3 hinged along one vertical edge as at 4. One preferred manner

of mounting the display device is to secure the door 3 to the side of the wall or other 55 stationary object so that the other part of the casing may be swung laterally on the hinges 4. The base of the globe 2 rests on the laterally extending flange 5, which 60 projects from the upper end of the casing 1, and within this globe is located an electric lamp 6 or the like, current for which may be furnished from any suitable source.

When the casing 1 is rectangular in cross 65 section, each of the several walls thereof with the exception of that formed by the door 3 is provided with a plurality of vertically spaced superimposed display openings 7. These openings are of such size 70 and shape as to readily permit of the display signs disposed within the casing being visible. Such signs may be of any preferred construction, for instance, they may consist of plates 8 having suitable advertising 75 painted, printed or otherwise formed thereon and secured over the openings 7 by means of rabbeted cleats 9 in which the plates are slidably mounted. In other words the inner surfaces of the walls of the casing 1 adjacent the openings therein are 80 provided with means for holding the plates 8 in such a manner that they can be readily interchanged. In this way advertising may be placed on display for a predetermined 85 period of time and readily substituted by other advertising matter at the expiration of such time.

I claim:

A display device comprising an upright 90 hollow post, having sides which taper uniformly from the ground to the top thereof, one of said sides being hinged to form a door, each of the other sides having a plurality of vertically aligned spaced window 95 openings, vertical rabbeted cleats disposed on the inner faces of the walls at each side of the window openings, and sign plates visible through said openings and slidably supported in said cleats so as to be removable and interchangeable, access being had for this purpose through said door. 100

In testimony that I claim the foregoing I have hereunto set my hand at Milwaukee, in the county of Milwaukee and State of 105 Wisconsin.

JULIUS L. MICHALSKI.
